(No Model.)

J. C. GUNN.

MAIL BAG.

No. 348,965.

Patented Sept. 14, 1886.

UNITED STATES PATENT OFFICE.

JOHN C. GUNN, OF KNOXVILLE, TENNESSEE, ASSIGNOR OF ONE-HALF TO
THOMAS EGAN, OF SAME PLACE.

MAIL-BAG.

SPECIFICATION forming part of Letters Patent No. 348,965, dated September 14, 1886.

Application filed May 24, 1886. Serial No. 203,139. (No model.)

To all whom it may concern:

Be it known that I, JOHN C. GUNN, a citizen of the United States, residing at Knoxville, in the county of Knox and State of Tennessee, have invented a new and useful Improvement in Mail-Bags, of which the following is a specification.

My invention relates to improvements in mail bags or pouches; and it consists of the peculiar combination and novel construction and arrangement of the various parts for service, substantially as hereinafter fully set forth, and particularly pointed out in the claims.

The object of my present invention is to provide a mail-bag with improved means for effectually excluding water, dirt, and other foreign matter from the bag when the mouth of the latter is closed, to provide means whereby one or more locks may be employed to effectually secure the mouth of the bag together and prevent any ill-disposed person from surreptitiously forcing the bag open, and to improve the bag in minor details of construction so that it will be simple and strong, as well as durable, easily and readily operated, and comparatively cheap of manufacture.

In the accompanying drawings, which illustrate a mail bag or pouch embodying my invention, Figure 1 is a perspective view of the device in its closed position. Fig. 2 is a like view of the device in its open position. Fig. 3 is a horizontal sectional view through the mouth of the bag or pouch on line α α of Fig. 1. Fig. 4 is an enlarged detail view of two of the hinged plates for the mouth of the bag; and Fig. 5 is a vertical sectional view through the plates shown in Fig. 4, fitted or connected together.

Referring to the drawings, in which like letters of reference denote corresponding parts in all the figures, A designates the bag or pouch, which is of the ordinary well-known class, and B the hinged plates, which are arranged at the open end or mouth of the bag and are adapted to be fitted snugly together to effectually close the mouth of the pouch and prevent the admission of water, dirt, and other foreign matter thereto.

In the accompanying drawings, I have shown a series of four plates, which are numbered from 1 to 4, inclusive; but it will be un-

derstood that I do not confine myself to the use of any particular number, as they can be varied to suit bags of different sizes.

The plates numbered 1 and 2 are arranged on one side of the bag, and the remaining plates, 3 and 4, are located on the opposite sides of the bag, and when the mouth of the bag is closed the plates 1 and 3 and 2 and 4 come or abut together to securely close the mouth of the bag. The plates 1 and 2 are each provided on their upper edges with inwardly-extending ribs or flanges C, which are formed integral or in one piece therewith, and the plates 3 and 4 are also provided with inwardly-projecting flanges D, which are similar to the flanges C, but are arranged at the lower edges of the plates 3 and 4, by which they are carried as clearly shown in the detail views Figs. 4 and 5. When the plates come together in the manner above described, the flanges C fit or project over the upper free edges of the plates 3 and 4, and the flanges D project beneath the lower edges of the plates 1 and 2, and by this peculiar construction and arrangement of the various parts all water and dirt are effectually excluded from the bag when the latter is closed, and a compartment or space, E, is provided between the plates B, as is obvious. The upper edges of open mouth of the bag A are fitted against the outer faces of the plates B, and the plates are permanently attached to the bag or pouch by means of rivets or other like suitable fastening devices, F. The inner surfaces of the plates B are further provided with an elastic packing, G, which is suitably secured thereto by means of the same rivets that secure the plates B and the upper edges of the bag or pouch together. This packing may be of rubber, leather, or other like suitable material, and when the mouth of the bag is closed the plates are fitted together, and the resilient packing entirely fills and closes the space E between said plates, and thereby aids in excluding water and dirt from the main compartment of the pouch, as will be very readily understood.

The sections 1 and 3 and 2 and 4 are hinged or pivotally connected together, so that the mouth of the bag or pouch can easily and readily collapse or close together, and the other ends of the said plates are hinged or

pivoted to plates H and I, which are arranged opposite to each other and rigidly secured to the upper ends of the bag by rivets or other like means. The plate H has the ends of the 5 sections or plates 1 and 2 pivotally connected thereto, and the plate I has the ends of the sections 3 and 4 connected therewith in like manner. The plate H is provided at its upper edge with an integral rib or flange, J, 10 which extends therefrom at right angles, and fits or lies over the upper edge of the plate I when the bag is closed together; and the plate H is further provided with an inwardly-projecting lug or staple, K, which is provided 15 with an opening, k, and a notch in its upper edge, which provides a shoulder, k', into which fits a bolt of a lock, L, that is carried by the plate I. The lock is of the ordinary or any preferred form, and it is concealed within or 20 by the plate I, and the said plate is provided with a slot, l, through which the staple passes, the eye of the staple or lug projecting or extending beyond the outer face of the plate I, so as to permit a padlock, M, of any preferred 25 form to be connected therewith and afford greater security against robbery. The lock L and the padlock M may be opened by one and the same key, or they may be opened by different keys, as is obvious.

3c The operation of my invention will be readily understood from the foregoing description, taken in connection with the drawings.

It will be seen that I provide simple and durable means for effectually excluding water 35 and other matter from the open mouth of the bag; that the free edges of the plates are protected from injury; that greater security is insured by the use of the two locks, which are arranged in a very convenient and compact manner, and that the various parts are 40 very strong and cheap.

Slight changes in the form and proportion

of parts may be made without departing from the principle of my invention.

Having thus fully described my invention, 45 what I claim as new, and desire to secure by Letters Patent, is—

1. The combination, with a mail bag or pouch, of the pivoted or hinged plates 1 and 2, provided with the inwardly-extended flanges C 50 at their upper edges, and the plates 3 and 4, arranged opposite the plates 1 and 2, and provided at their lower edges with the inwardly-projecting flanges D, said flanges C D fitting over and beneath the free edges of the pivoted or hinged plates, to form a closed space or chamber intermediate of the plates, substantially as described.

2. The combination, with a mail bag or pouch, of the hinged plates provided with the extended flanges C D, arranged, as described, to fit over and beneath the free edges of the plates, and the packing secured to the plates, within the flanges thereof, to completely fill the space or chamber formed by the plates, substantially 65 as described.

3. The combination of the plates or sections B, flexibly connected together and having the flanges, the plates H and I, to which the said sections are hinged, the plate H, having a 70 notched staple or lug and an inwardly-extended flange or ledge, and the plate I, carrying a lock and having a slot through which the staple is passed to receive an additional or auxiliary lock, all arranged and combined substantially as described, for the purpose specified.

In testimony that I claim the foregoing as my own I have hereto affixed my signature in presence of two witnesses.

JOHN C. GUNN.
